UNITED STATES PATENT OFFICE.

LILLIAN McNARY, OF SALEM, OREGON.

DESIGN FOR A BADGE.

45,538.

Specification for Design.

Patented Mar. 31, 1914.

Application filed January 19, 1914. Serial No. 813,117. Term of patent 14 years.

To all whom it may concern:

Be it known that I, LILLIAN McNARY, a citizen of the United States, residing at Salem, in the county of Marion and State of Oregon, have invented a new, original, and ornamental Design for Badges, of which the following is a specification, reference being had to the accompanying drawing, in which a face view of the badge is shown.

I claim:

The ornamental design for a badge as shown.

In testimony whereof I affix my signature in the presence of two witnesses.

LILLIAN McNARY.

Witnesses:

JOSEPHA HOLMES,
REX A. TURNER.
